UNITED STATES PATENT OFFICE.

ROBERT W. SIKKING, OF EAST ST. LOUIS, ILLINOIS.

LOOSE SEAT-COVER.

1,326,216.

Specification of Letters Patent.

Patented Dec. 30, 1919.

Application filed September 14, 1916. Serial No. 120,031.

To all whom it may concern:

Be it known that I, ROBERT W. SIKKING, a citizen of the United States, residing in the city of East St. Louis, county of St. Clair, 5 and State of Illinois, have invented new and useful Improvements in Loose Seat-Covers, of which the following is a specification.

This invention relates to loose seat-covers 10 and more particularly to detachable or slip covers for the seat-cushions of automobiles and the like.

The usual practice is to make counterpart 15 pattern covers and fit them to the seats, which is quite troublesome and expensive in some cases owing to the peculiar shapes and contours of the seats in automobile bodies of different construction. So, too, it 20 is difficult to laundry or chemically clean made-up covers of this character, and, on account of shrinkage of the cloth in the cleaning process, the covers sometimes cannot be properly refitted to the seats. Owing to this 25 last mentioned disadvantage and also by reason of there being some variation in the size and contour of the seats, even in cars of the same model, it has been found impractical to make stock covers for any particular model unless they are made so loose 30 as not to present a neat and trim appearance when applied.

The present invention, therefore, has for its objects to produce a cover capable of adjustment to fit seats of cars of different 35 models or makes, which is readily applied and can be easily laundried and refitted to the seat; and to attain certain advantages which will hereinafter more fully appear.

The invention consists primarily in a seat 40 cover made in separable pieces or sections each of which may be separately handled for cleaning, and it further consists in the parts and in the combinations and arrangements of parts hereinafter described and claimed.

45 In the accompanying drawings illustrating an adaptation of the invention,—

Figure 1 is an outer face view of the middle section of the cover;

Figs. 2 and 3 are similar views, respectively, of the right and left side cushion covers;

Fig. 4 is a fragmentary section, on an enlarged scale, on the line 4—4 of Fig. 2;

Fig. 5 is a similar view on the line 5—5 of Fig. 1;

55 Fig. 6 is a detail view of the wire bail for supporting the upper marginal portions of the cover sections;

Fig. 7 is a view of the rod for weighting the lower marginal portion of the curtain or 60 flap portion of the middle cover section which hangs in front of the seat;

Fig. 8 is a view of the bail or frame which holds the cover under the seat-cushion;

Fig. 9 is a fragmentary view, partly in 65 section, looking at the under face of the cover, showing the manner of securing the meeting corners of two sections of the cover together;

Fig. 10 is a perspective view, partly in 70 section, illustrating the cover partially applied; and

Fig. 11 is a similar view showing the appearance of the cover when fully applied.

For ordinary seats having but one seat-cushion and back and side cushions, the cover will preferably be constructed of three sections, namely, a middle section 1 and right and left side sections 2 and 3, respectively.

80 The middle section 1 has a portion 4 which overlies the back cushion, and a curtain or flap 5 which overhangs the edge of the seat-cushion and extends well down in front of the seat, while at opposite sides of the body 85 portion are flaps 6 and 7 arranged and adapted to be tucked in about the ends of the seat-cushion.

The end marginal portion 8 of the curtain 5 is hemmed over upon itself to provide a 90 tube for the reception of a rod 9 which weights the curtain down, while the end marginal portion 10 of the upper flap 4 is likewise folded over and stitched throughout the extent thereof except for a short distance inward from the ends, as indicated at 95 11, thereby forming a tube between the points 11 and loose flaps between the points 11 and the ends. The tube is best shown at 12 and the flap at 13 in Fig. 5. The flaps 100 13 are provided with a series of closely arranged eyelets 14 for the application of

lacings which will be more fully set forth later on, and at the middle of the cover and perhaps at other places intermediate its ends additional eyelets 15 may be provided 5 adjacent to the tubular portion 12.

The upper marginal portions of the side cover sections 2 and 3 are made to conform as nearly as possible to the contour of the side cushions and are hemmed over to provide tubes 16 similar to the tube 12, as best shown in Fig. 4. At the ends of the sections 2 and 3 which coöperate with the middle section 1 a series of eyelets 17 are closely arranged similar to the eyelets 14, and at the 15 opposite ends and at suitable places intermediate the ends the sections 2 and 3 are provided with additional eyelets 18 and 19.

The several cover sections are made large enough for the overlapping of their meeting marginal portions when applied to the seat. In assembling the sections the corners of the sections 2 and 3 where the eyelets 17 occur are inserted under the flaps 13 to the proper distance to fit the cover to the 20 seat and interlaced with said flaps by strings 25. The upper marginal portions of the cover sections are then arranged around the upper edges of the back and side seat cushions, after which the side sections 2 and 3 30 are brought down and smoothed over the side cushions, and the lower marginal portions of said sections 2 and 3 are turned inward, so as to rest on the top of the seat, the seat-cushion being removed. The middle section 1 is then adjusted and in doing so the portion 4 is brought down over the back cushion with its side marginal portions 21 overlapping the meeting marginal portions of the side sections 2 and 3 in the corners or 35 crotches where the back and side cushions merge. The middle portion 1 is brought down close to the seat and folded up from there, as best shown in Fig. 10. The seat-cushion 22 (shown in Fig. 11) is then placed 40 on the seat, over the inturned marginal portions 23 of the side sections 2 and 3 and back against the upfolded portion of the section 1. The body portion of the section 1 is then smoothed neatly over the top of 45 the seat-cushion, and the flap 5 is dropped in front of the seat, after which the side flaps 6 and 7 are tucked in about the ends of the seat-cushion. The covering is now completed, as shown more clearly in Fig. 11.

To fasten the cover about the upper edges of the seat it is only necessary to lace strings 24 through the respective eyelets and tie said strings to the buttons or other fastenings which are ordinarily provided for the attachment of the storm curtains or to the top-supporting irons, or, if necessary, special buttons or fastenings may be provided on the body of the car.

To more securely hold the cover in place it

is preferable to utilize a bail or frame 25 (see Fig. 8) whose end portions 26 are made to rest on the marginal portions 23 of the side cover sections 2 and 3 and up close to the cushion, while the middle cover section 1 is brought under the middle portion of the bail (see Fig. 10). The ends of the bail are rebent, as at 27, so as to underlie the seat-cushion 22 which serves to hold the bail securely in place. It is also preferable to sleeve the upper marginal portions of the 75 cover sections on a bail or frame 28 which is made to conform to the contour or marginal lines of the seat back and sides (see Fig. 6). Both of these frames 25 and 28 are preferably made adjustable. That is, 80 they are each made in two sections with their meeting ends overlapping and in slidable engagement, so as to be extensible and contractible.

If desirable, the curtain or flap 5 may be 85 tied down or otherwise fastened in front of the seat, but it has been found that the mere weighting thereof by the insertion of the rod 9 in the tubular portion 8 serves the purpose. In some cases, also, the side cover sections 2 and 3 may be slitted, as indicated by the broken line 29, so that the one half may be made to overlap the other in conforming 90 the cover to the cushion, but this is not necessary in many cases.

The construction admits of considerable further modification within the spirit and scope of the invention as defined in the appended claims. For example, while three cover sections are ordinarily adequate for 100 the usual seat construction, obviously a greater number of sections is necessary to neatly cover seats of certain distinctive styles, particularly some drivers' seats which are divided by a ridge in the middle. In 105 such an instance, there will be employed two side sections like 2 and 3, two like section 1, and one plain strip somewhat elongated and relatively narrow, which latter is to cover the ridge. Therefore, it is understood that 110 the invention is not limited to the specific construction and arrangement shown in the accompanying drawings.

What is claimed is:

1. A divided slip cover for automobile 115 seats and the like, the same comprising a multiplicity of separable flat sections, the upper marginal portions of said sections being respectively shaped to conform to the contour of, and detachably and adjustably 120 secured about, the marginal portions of the back and sides of the seat, and the meeting marginal portions of said sections being adjustably overlapped flatwise.

2. A divided slip cover for automobile 125 seats and the like, the same comprising a multiplicity of separable flat sections, the upper marginal portions of said sections be-

- ing respectively shaped to conform to the marginal contour of the back and sides of the seat, and the meeting marginal portions of said sections being adjustably overlapped 5 in assembled relation, means for detachably securing said sections together, and means for detachably securing the upper marginal portions of said sections to the outside of the automobile body.
- 10 3. A divided slip cover for automobile seats and the like, the same comprising a middle section and separable side sections, the individual sections being normally flat and having one of their marginal portions 15 shaped to respectively conform to the upper marginal contour of the back and sides of the seat, and the meeting marginal portions of said sections being adjustably overlapped in assembled relation, means for detachably securing said sections together, means for detachably securing the upper marginal portions of said sections to the outside of the automobile body, and means for releasably holding the lower portions of said sections 20 respectively between the bottom cushion and the back and side cushions of the seat.
4. A loose cover for automobile seats and the like, the same comprising a middle section and two side sections, said sections being separable and their meeting marginal portions overlapping in assembled relation, means for adjustably securing the meeting upper corner portions of said sections together, and means for securing the upper marginal portions of said sections to the outside of the automobile body, said side sections being brought down over the side cushions with their lower marginal portions underlying the end portions of the bottom cushion, said middle section being brought down over the back cushion, behind the bottom cushion, thence up and over the top of the bottom cushion, and down in front of 45 the seat.
5. A loose cover for automobile seats and the like, the same comprising a middle section and two side sections, said sections being separable and their meeting marginal portions overlapping in assembled relation, means for adjustably securing the meeting upper corner portions of said sections together, and means for securing the upper marginal portions of said sections to the outside of the automobile body, said side sections being brought down over the side cushions with their lower marginal portions underlying the end portions of the bottom cushion, said middle section being brought 50 down over the back cushion, behind the bottom cushion, thence up and over the top of the bottom cushion, and down in front of the seat, and said middle section having side flaps tucked in about the ends of the bottom cushion,
6. A loose seat-cover for automobiles and the like, the same comprising a middle section and two separable side sections, the upper marginal portions of said sections being tubular and the meeting marginal portions 70 of said sections overlapping in assembled relation, a bail on which the tubular portions of said sections are sleeved, said bail conforming to the contour lines of the upper edge portions of the seat, means for securing the meeting upper corners of said cover sections together, and means for securing the upper marginal portions of the cover sections to the automobile body.
7. A loose seat-cover for automobiles and the like, the same comprising a middle section and two separable side sections, the upper marginal portions of said side sections being tubular, and the upper marginal portion of said middle section being 85 tubular throughout its extent except for portions near the ends where flaps are formed, the meeting marginal portions of said cover sections overlapping in assembled relation and the corner portions of said 90 side sections underlying the flaps on said middle section, means for adjustably securing said corner portions and flaps together with the tube openings of said sections in alinement, a bail on which said tubular portions of said cover sections are sleeved, said, bail conforming to the contour lines of the upper edge portions of the seat, and means for securing the upper marginal portions of the cover sections to the automobile body. 100
8. A loose seat-cover for automobiles and the like, the same comprising a middle section and two separable side sections, a bail conforming to the marginal lines of the bottom cushion support, the ends of said bail 105 being rebent in its plane so as to underlie the bottom cushion, the meeting marginal portions of said cover sections overlapping in assembled relation and the meeting upper corner portions of said sections being 110 adjustably secured together, the upper marginal portions of said cover sections being secured to the automobile body in the region of the upper edge portions of the seat, said side cover sections being brought 115 down over the side cushions with their lower marginal portions under the end portions of said bail and resting on the bottom cushion support, and said middle cover section being brought down over the back cushion, 120 under the middle portion of said bail and behind the bottom cushion, thence up over the top of the bottom cushion, and then down in front of the seat, said middle cover section having side flaps tucked in about 125 the ends of the bottom cushion.
9. An adjustable loose cover for automobile seats and the like, the same comprising separable sections, means for detachably securing said sections together, an adjustable 130

- frame to which the upper marginal portions of said sections are fitted throughout their extent, said frame conforming to the marginal lines of the seat, and a second adjustable frame conforming to the marginal lines of the bottom cushion support and having a portion underlying the bottom cushion, por-

tions of said cover sections in proximity to the back and ends of the bottom cushion being secured under said second-mentioned frame.

In testimony whereof, I have hereunto set my hand.

ROBERT W. SIKKING.
